UNITED STATES PATENT OFFICE

HUGH C. BROWN, OF ASHEVILLE, NORTH CAROLINA

DESIGN FOR A COFFEE TABLE

Application filed October 21, 1929. Serial No. 33,125. Term of patent 3½ years.

To all whom it may concern:

Be it known that I, HUGH C. BROWN, a citizen of the United States, residing at Asheville, in the county of Buncombe and State of North Carolina, have invented a new, original, and ornamental Design for a Coffee Table, of which the following is a specification, reference being had to the accompanying drawing, forming part thereof, in which—

I claim:

The ornamental design for a coffee table as shown.

HUGH C. BROWN.
